United States Patent Office.

HIRAM SMITH, OF NORWALK, OHIO.

Letters Patent No. 96,982, dated November 16, 1869.

IMPROVEMENT IN JOINTED PIPE-CONNECTIONS.

The Schedule referred to in these Letters Patent and making part of the same.

To all whom it may concern:

Be it known that I, HIRAM SMITH, of Norwalk, in the county of Huron, and State of Ohio, have invented certain new and useful Improvements in Water-Tank Pipe-Joint for Railroads; and I do hereby declare that the following is a full and complete description of the same, reference being had to the accompanying drawings, making part of this specification, in which—

Figure 1 is a side view of the pipe and joint.

Figure 2, a view of the top.

Like letters of reference refer to like parts in the different views.

This invention relates to a jointed connecting-pipe, whereby the tender of a locomotive is supplied with water from the reservoir, the joint in the pipe being such, that said pipe is readily and easily adjusted to the position and height of the tender, as hereinafter more fully described.

The conducting-pipe, or conductor referred to, is constructed in two sections, A B, fig. 1, section A being of larger diameter than B, and into which the end of B is screwed, as indicated by the dotted line *a*.

The end or head C, introduced into section A, is provided with an elastic packing, *a*, fig. 2, whereby the head or end of the pipe is made water-tight in its connection with the pipe A, and which also allows of its being moved about therein for the purpose of adjusting the pipe to the tank of the tender.

The two sections of pipe are secured to each other by means of the curved standard D. The lower end of said standard is fitted in the boss E, in which it turns, or it can be secured tightly therein by a set-screw in the side of the boss.

The upper end of the standard is connected, by a hinged joint, to a stem, F, loosely fitted in a stay, G, in which it turns, and is prevented from coming out by a nut, H, screwed to the stem below the stay.

Having thus described the connection of the pipe or conductor, the practical operation of the same is as follows, viz:

Section B is screwed in the side of the reservoir, so that it may project forward from the side of the building.

When not in practical use, section A is detached and swung around at right angles to section B, as shown in fig. 2, against the side of the house.

When it is required to use the conductor, section A is swung around from its right-angle position to section B, until the two sections are in line with each other. Now, on depressing the extreme end of A, the head or end C of section B will enter the pipe A, as indicated by the dotted line *a*, fig. 1, in which it will be seen that the pipe A is deflected downward from a horizontal line, and which, at the same time, may be turned laterally more or less, as the position of the tender on the track may require, or it may be

elevated or depressed, as the height of the tender may render necessary.

This elevation and depression of section A are attained by the jointed connection of the curved standard to the stem F, and the lateral movement to the freedom allowed the stem in the stay; hence, by this combined movement of the section, it will be obvious that the pipe can be easily adjusted to tenders of different heights, which have an average difference of only a few inches; and, furthermore, should the tender not stand exactly in range with the discharging-pipe B, the section A can be turned to either direction, so as to make the proper connection with the tender for receiving water.

It will be observed that the section A is slightly tapering, it being large at the end, receiving the end of section B, the purpose of which is to cause the packing *a* to fit closely, on the introduction of the head, and thereby prevent leakage.

It will also be seen that section A is smaller at or near the head than it is at the opposite end. By this means, greater freedom is obtained to the pipe in its lateral movement. Therefore, the engine can be supplied with water, though the tender may not be stopped directly opposite the conducting-pipe.

By the use of this jointed water-pipe, trouble and delay in the movement of the train are avoided, but which are unavoidable in supplying the tender with water in the ordinary way, as it is necessary to stop the engine at the exact joint to bring the conducting-pipe so as to make the connection; and should a canvas or other flexible pipe be used, in order to adapt the pipe to the height of the tender and its position on the track, such pipe is soon worn out, or becomes injured, leaky, and worthless, which, however, cannot be the result with the pipe herein described. It being made wholly of metal, is, therefore, strong and durable, and, being provided with the flexible joint, is easily and readily adjusted to the tender.

In order to prevent section A from being swung around too far, and thereby cause unnecessary strain to be exerted upon the joint, a stop, *c*, fig. 2, is arranged on the stay, immediately back of the stem, against which it will strike on coming around, thereby restraining it from going too far.

Each section of the pipe (as above said) is made tapering, but which, however, may be made straight, if so desired.

What I claim as my improvement, and desire to secure by Letters Patent, is—

The sections of pipe A B, standard D, and swivelled or hinged stem F, as arranged and combined, to operate conjointly in the manner substantially as described, and for the purpose set forth.
